UNITED STATES PATENT OFFICE.

GEORGE JOHNSON-JERVIS, OF NEW YORK, N. Y.

GAME APPARATUS.

972,382.

Specification of Letters Patent. Patented Oct. 11, 1910.

Application filed January 3, 1910. Serial No. 536,061.

To all whom it may concern:

Be it known that I, GEORGE JOHNSON-JERVIS, a citizen of Great Britain, residing at New York, in the county of New York 5 and State of New York, have invented certain new and useful Improvements in Game Apparatus, of which the following is a specification.

My invention relates particularly to apparatus for playing a game simulating naval operations.

The accompanying single sheet of drawings illustrates one form of apparatus embodying the invention which will be more 15 clearly understood from the description hereinafter set forth.

Figure 1, is a plan view of a board or chart or table on which the game is played. Figs. 2, 3 and 4 are side views of the pieces 20 for moving on the board and representing respectively a battleship, a cruiser and a torpedo boat or destroyer. Fig. 5, is a perspective view of a cup and cube constituting one form of chance device for determining 25 the results of gun fire. Fig. 6, represents a number of perforated disks for attaching to the vessels to indicate hits thereon.

The board or chart or table which for convenience will be termed a chart represents 30 a body of water and the contiguous territory about which the naval operations take place. There are two or more ports such as 1 and 2 representing the base of operations of opposing naval forces. I also prefer to 35 provide some intermediate area such as an island or group of islands 3 serving as a refuge or rendezvous for the vessels and which constitutes a barrier to operations. The area representing the water is preferably 40 divided by a series of transverse and longitudinal lines into a plurality of relatively small squares.

Each player is provided with a plurality 45 of pieces representing vessels for instance one destroyer, two cruisers, and one battleship and the vessels of the opposing forces are suitably distinguished from one another for instance by difference in color. The 50 rules of the game provide that these different vessels shall be permitted to move different distances in a single turn for instance, a destroyer being naturally of high speed is permitted to be moved 6 squares or less in one turn, a cruiser being relatively slower 55 may be moved 4 squares or less in one turn and a battleship somewhat slower still is

permitted to move 2 squares or less in one turn. This capacity for moving may conveniently be termed radius of operation. A vessel may be moved in any direction between parallel lines on the chart or in straight lines along the diagonals of the squares of the chart. The vessel is considered to be upon the square on which its bow rests and in moving, the square on which it rests is not included within the count. At the beginning of the game the vessels are within their home ports and each player in turn moves his vessels from his port toward his opponent, moving such one of his vessels as he desires. As the opposing vessels approach one another they come within range of gun fire. For this purpose the different types of vessels are considered to have different ranges of action for instance the 75 destroyer can shoot only 2 squares, the cruiser 6 squares and a battleship 8 squares. When a vessel moves within range of action of the opponent's vessel the opponent may open fire by operating the chance device to 80 determine whether or not his vessel hits the other. Any suitable form of chance device such as dice, spinning-wheel or dial may be employed. I have illustrated a simple cube having the word "Hit" upon each of a 85 plurality of sides and being blank on the other sides. If the side marked "Hit" comes uppermost when the cube is thrown from the cup on to the chart the vessel firing is considered to have hit the opposing 90 vessel whereupon one of the hit rings or disks shown in Fig. 6 is placed over the mast of the vessel struck. The turn then passes to the other player and if his vessel is of the same type and has the same gun 95 range as his opponent he may return the fire. Of course a vessel having a short gun range may come within the range of fire of an opponent without itself being able to fire, for instance a destroyer having a gun range 100 of 2 squares may be moved within 8 squares of a battleship whereupon the battleship may begin fire which the destroyer cannot return until it approaches within 2 squares of the battleship. The different vessels are 105 considered to have different resistance to gun fire and are therefore permitted to be subjected to different numbers of hits for instance, a destroyer is put out of commission by two hits, a cruiser may require four hits 110 and a battleship six hits. A vessel receiving the maximum number of permitted hits is

withdrawn from the game. It is also arranged that a vessel after receiving a lesser number of hits may withdraw from the engagement if desired and return by regular moves to its home port for repairs. The hit rings are thereupon removed and the vessel may go back into engagement. A vessel may not fire over another of its own fleet and may not fire over land.

10 By having the pieces representing the vessels of a larger size than the squares on the chart I am able to introduce a further feature of interest into the game. In this case while the vessel's moving and firing is counted from the square on which its bow rests it may be fired at by any vessel whose bow is in a straight or diagonal line with any part of it. Such a vessel in its next turn may be moved out of range by swinging about its 20 bow or moving in the usual manner.

The different types of vessels may be readily distinguished from one another in any suitable manner as for instance by size, design or number of smoke-stacks. I also 25 wish it understood that each vessel may be given a different radius of action or different gun range or a different resistance to hits than is herein set forth so long as the principles of operation are embodied substantially as described.

Another variation in the rules which gives increased activity to the game is to permit the player to fire immediately upon coming 35 into range of an opponent's vessel. This prevents the players from totally avoiding an action by successively retiring.

What I claim is:-

1. A game apparatus comprising a chart having an operating surface consisting of a 40 water area divided into spaces and having ports for the opposing fleets, a plurality of pieces for each player representing vessels of different radii of action and different gun range and means for determining the hits.

45 2. A game apparatus comprising a chart having a playing surface and fleets for the opposing players each consisting of a plurality of vessels having different gun ranges and different resistance to hits, means for 50 determining hits and devices for attaching to the vessels for indicating hits.

3. A game apparatus comprising a chart constituting a playing surface, a fleet of vessels for each of the opposing players, 55 each fleet having vessels of different radii of action, different gun range and different resistance to hits and means for determining hits.

4. A game apparatus comprising a chart constituting a playing surface, a fleet of 60 vessels for each of the opposing players, each fleet having vessels of different radii of action, different gun range and different resistance to hits and means for determining hits and means for indicating hits upon the 65 vessels.

5. A game apparatus comprising a chart having its principal area divided into squares extending in transverse and longitudinal directions, a fleet of vessels for each 70 of the opposing players each fleet consisting of a plurality of vessels of different sizes for moving on the chart and means for determining hits.

6. A game apparatus comprising a chart 75 having its principal area divided into transverse and longitudinal series of squares, a plurality of fleets of vessels each fleet consisting of a plurality of vessels some of which are of greater length than the dimensions of said squares and means for determining hits substantially as described.

7. A game apparatus comprising a chart having its principal area representing water divided into a plurality of spaces and having 85 an area representing land constituting a barrier, a plurality of fleets of vessels each fleet consisting of a plurality of vessels having different ranges of gun fire and means for determining hits.

8. A game apparatus comprising a chart having its principal area representing water divided into a plurality of spaces and having an area representing land constituting a barrier, a plurality of fleets of vessels each 95 fleet consisting of a plurality of vessels having different ranges of gun fire, means for determining hits and some of the vessels in a fleet having different radii of action from other vessels in the fleet.

9. A game apparatus comprising a chart having its principal area representing water divided into a plurality of spaces and having an area representing land constituting a barrier, a plurality of fleets of vessels each 105 fleet consisting of a plurality of vessels having different ranges of gun fire, means for determining hits and some of the vessels in a fleet having different radii of action from other vessels in the fleet and different resistance to hits.

GEORGE JOHNSON-JERVIS.
